HOUSING FOR AIRCRAFT SEARCHLIGHT

Richard D. Wood, Pasadena, Calif., assignor to Optical
Radiation Corporation, Monrovia, Calif.

Filed Oct. 23, 1970, Ser. No. 55,618

Term of patent 14 years

Int. Cl. D26—06, 03

U.S. Cl. D48—32

FIG. 3

FIG. 2

FIG. 4

FIG. 1

FIG. 1 is a side elevational view of a housing for an aircraft searchlight showing my new design;

FIG. 2 is a perspective view thereof on a reduced scale;

FIG. 3 is a front elevational view thereof on a reduced scale;

FIG. 4 is a rear elevational view thereof on a reduced scale.

I claim:

The ornamental design for a housing for aircraft searchlight, as shown.
